UNITED STATES PATENT OFFICE.

HARRIE P. WOOD, OF LEONIA, NEW JERSEY.

WRAPPER-PASTING DEVICE.

Application filed July 22, 1926. Serial No. 124,199.

The present invention relates to new and useful improvements in wrapping devices, and it pertains more particularly to a new and improved means for facilitating the 5 wrapping of magazines, books and the like for mailing.

It is one of the objects of the invention to provide a new and improved device which will greatly expedite the wrapping of magazines, books and similar articles; will eliminate the paste-pot and brush commonly employed for this purpose and also the inconvenience thereof; will apply the paste singly and uniformly to the wrappers and without 15 waste; will permit of replenishing the supply of wrappers without waste of paste, and is so constructed as to fold into a compact structure for the purposes of transportation or storage.

With the above and other objects in view, which will appear as the nature of the invention is better understood, reference is had to the accompanying drawings which illustrate the invention in its preferred form, and in 25 which—

Figure 1 is a view in side elevation of the device with its several parts shown in operative position;

Figure 2 is a top plan view thereof;

Figure 3 is a view in elevation taken at right angles to Figure 1, and partly broken away, the several parts being shown in their operative position;

Figure 4 is a detail view in elevation of a portion of the device showing the paste receptacle in its elevated position; and

Figure 5 is a view in elevation showing the device in its folded position.

Referring more particularly to the drawings, the wrappers which are to be applied to the magazines or similar articles to be wrapped, are positioned upon a suitable base 10, a stack of said wrappers being designated by the reference numeral 12.

To provide for folding the device, in order that a relatively small package may be made thereof, which is of great convenience in shipping or storing the device, the base 10 may be formed of a plurality of sections, such as 14, 16 and 18, preferably pivotally 50 connected together as at 20.

Carried by the section 18, and projecting vertically therefrom, there is a sheet metal member 22 bent upon itself in such a manner as to provide a forward straight wall 24 and a rear angular wall 26. At the point

where this sheet metal member is bent upon itself, it is so formed as to provide a bearing 28 in which is mounted a transversely extending rod or the like 30.

The rod 30, heretofore mentioned, serves as the support of a suitable frame-work which, in turn, carries the paste receptacle or tank, and this rod forms the means about which the frame swings to move the paste receptacle or tank to its inoperative position. This frame comprises two brackets 38 held in spaced relation to each other by rods 34 which are secured in the body portion of the brackets by any suitable means, such as nuts 36. The brackets each comprise a body portion 38 having end extensions 40 which are perforated at their forward ends. The rear end of each of these extensions 40 is formed with a lug 46 undercut as at 47 for 75 the reception of the right angular ends 44 of rods 42, which latter form the carriers and guides for a paste receptacle or tank 50 to be hereinafter specifically described. By disengaging these extensions 44 with their respective lug 46, the rods 42 may be removed from their respective bracket members.

These brackets are each preferably provided with an elongated lug 31 having two 85 perforations which construction permits of a bracket being used upon either side of the machine merely by reversal or turning of the bracket end for end.

The paste receptacle or tank is designated 90 by the reference numeral 50, and it is mounted for sliding movement upon the rods 42 by means of brackets 52 suitably secured to the end walls 54 thereof, and in which the rods 42 are capable of sliding movement. 95

The front wall of the paste receptacle or tank is preferably straight, while the bottom wall is formed with an inclined portion 56 and a straight portion 58, and it is in this straight portion that the paste discharge slots 59 are 100 formed. While in the present instance, two of these paste discharge slots are provided, it is obvious that a single slot may be employed in lieu thereof, if desired. The top 105 of the paste receptacle or tank is partially closed by the curved wall 60, the forward edge of which terminates short of the upper edge of the front wall to provide a filling opening 62.

By constructing the paste receptacle or tank in the manner described, it will be seen 110 that it may be moved to the position in which

it is shown in Figure 4 without danger of running over or spilling of any of the contents thereof, the level of the paste therein falling to a point below the forward edge 5 of the wall 60 and the discharge slots 58.

In operation, the paste receptacle or tank is adapted to rest upon the top wrapper of the stack 12 of wrappers, with said top wrapper closing the discharge slots 59 sufficiently to prevent any flow of paste from the paste receptacle or tank 50. To prevent accidental forward movement of the framework about its pivotal point, a latch is provided, and this latch may consist of a suitable dog or pawl 64 pivotally mounted as at 66 and having a notched end 68 adapted to engage the lower extension 40 of one of the brackets 38. If desired, there may be two of these latches, they being arranged one at 20 each side of the base 10, but under actual operating conditions, one latch has been found sufficient.

To prevent accidental backward movement of the frame about its pivotal point, 25 a stop 67 is provided, and this stop is carried by the base 10 and so positioned as to be engaged by the lower lug 46 of one of the brackets 38.

For supporting the paste receptacle or tank carrying frame in the elevated position in which it is shown in Figure 4, a hinged prop is provided, and this hinged prop comprises two members 70 and 72 hingedly connected together as at 74, the 35 member 70 being pivotally connected as at 76 to one of the brackets 38, the member 72 being pivotally connected to the base 10 as at 78.

As heretofore stated, the paste receptacle 40 or tank rests upon the upper wrapper of the stack 12 of wrappers, and to insure proper positioning of the stack of wrappers relative to the discharge slots of the paste receptacle or tank, a suitable guide is provided.

One form of guide which has been found 45 very effective in actual practice is a ribbed rubber mat, such as designated by the reference numeral 80 in the drawings, and said mat 80 is suitably secured to the base 10 preferably 50 with its ribs extending longitudinally of said base. This guide mat 80 is preferably of the same width as the wrappers to be used which width it will be noted by reference to Figure 2 is greater than the combined 55 lengths of the discharge slots 58 of the paste receptacle or tank 50. Thus it will be seen that if the several wrappers in the stack 12 are aligned with one another, and the stack positioned with its sides in alignment with 60 the side edges of the guide mat 80, the top wrapper will, at all times, close the ends of discharge slots 58 and prevent leakage or waste of the paste therefrom.

In use with the several parts in the position in which they are shown in Figure 1,

the magazine or other article to be wrapped is placed upon the top wrapper of the stack 12 of wrappers and the free end of the wrapper passed around the same. During the operation of wrapping the article, the wrapper 70 is withdrawn from beneath the paste receptacle or tank which action spreads paste upon that end of the wrapper occupying a position beneath the paste receptacle or tank. When the wrapper has been completely withdrawn from beneath the paste receptacle or tank, the said paste receptacle or tank rests upon the next lower wrapper in a position to deposit paste thereon as it is withdrawn from the stack. 75 80

When it is desired to clean the paste receptacle or tank, it is only necessary to disengage the extensions 44 of the rods 42 with their respective lugs 46, remove the rods from the frame, leaving the paste receptacle 85 or tank free to be removed from the device.

Referring to Figure 5 of the drawings, it will be noted that in the folding of the device into compact form for shipping or storing purposes, the section 16 is folded into 90 parallelism with the brackets 38 with the section 14 overlying the paste receptacle or tank 50 and the brackets 38 as shown.

From the foregoing, it is apparent that the present invention provides means by 95 which magazines, books or other articles may be more expeditiously wrapped than is possible by employing the paste-pot and brush as in the old method, eliminating all waste and thus resulting in a clean and sanitary 100 operation.

While in the present application the invention has been illustrated in its preferred 105 form, it is to be understood that the invention is not limited thereto but may be embodied in other forms within the scope of the appended claims.

What is claimed as new is:

1. In a device of the character described, 110 a suitable base, a frame mounted for swinging movement relative to said base, a plurality of vertically arranged guides mounted in said frame, and a paste receptacle or tank slidably mounted on said guides.

2. In a device of the character described, a 115 wrapper supporting base, a frame mounted on said base and having swinging movement to a position above the base, means for retaining said frame against swinging movement relative to said base in either of its positions, vertically arranged guides mounted in said frame, and a paste receptacle or tank mounted for sliding movement on said guides.

3. In a device of the character described, 120 a wrapper supporting base, a frame pivotally mounted on said base, and adapted to swing to elevated position in spaced relation to said base, means for supporting said frame in said elevated position, a plurality 130

- of vertically arranged guides mounted in said frame, and a paste receptacle or tank slidably mounted on said vertically arranged guides.
5. In a device of the character described, a base, a hinged frame mounted for swinging movement thereon, a plurality of vertically arranged removable guides carried by said frame, and a paste receptacle or tank 10 removably associated with said vertically arranged removable guides.
5. In a device of the character described, a base, a hinged frame mounted for swinging movement thereon to a position above 15 said base, means for supporting said frame in its elevated position, a paste receptacle or tank slidably mounted on said frame, and means permitting removal of said paste receptacle or tank when said receptacle carrying frame is in either position to which it is capable of movement.
6. In a device of the character described, a base comprising a plurality of hinged sections, a support carried by one of said sections, a frame pivotally mounted upon said support, a paste receptacle or tank slidably mounted upon said frame, means for supporting said frame in its elevated position, and means for preventing movement of the 30 frame to its vertical position.
7. In a device of the class described, a base, a paste receptacle or tank mounted for pivotal movement toward and away from said base, said paste receptacle having a discharge opening therein, and a wrapper sup- 35 porting guide mat carried by said base, and so positioned with respect to the slot in the paste receptacle or tank as to provide a guide by which a stack of magazine wrappers may be properly positioned with respect to the 40 discharge opening of said paste receptacle or tank.
8. In a device of the class described, a base comprising a plurality of sections hingedly connected together, a support carried by one of said base sections, a frame pivotally mounted in said support, and a paste receptacle or tank carried by said frame, said support, pivoted frame, and paste receptacle or tank being so arranged 45 as to permit of the remaining sections of said base folding therearound substantially as described.
9. In a device of the character described, a base, a support carried thereby, a frame pivotally mounted on said support and a paste receptacle or tank carried by said pivoted frame and normally occupying a position in a vertical plane but movable with said frame to a position in a horizontal 50 plane above the base, and means for retaining said frame in either of its positions, said paste receptacle or tank having an open side and being of such cross-sectional shape that in either its vertical or horizontal position, 55 its contents will not be discharged from the open side thereof.

Signed at New York, N. Y., this 20th day of July, 1926.

HARRIE P. WOOD.
